FIG. 1

FIG. 2

FIG. 3

FIG. 4

UNITED STATES PATENT OFFICE

2,004,570

LOOSE LEAF BINDER

George H. Dawson, Chicago, Ill., assignor to Wilson-Jones Company, Chicago, Ill., a corporation of Massachusetts

Application October 9, 1933, Serial No. 692,747

16 Claims. (Cl. 129—24)

This invention relates to loose leaf binders, and more particularly to a lever adapted to move the sheet retaining prongs of a loose leaf binder to closed position.

6 In loose leaf binders of the ring type, it has been customary to provide a lever for opening the prongs. However, heretofore it has been necessary for the user to snap the prongs shut by manual pressure on the prongs themselves. This is not particularly objectionable in cases of binders of small capacity where the prongs are held under comparatively light tension. In the case of binders of large capacities it is necessary to provide heavy tension on the prong plates to retain 10 the contents in the binder under ordinary conditions. Consequently it is quite a task for a girl to close the prongs of a binder of this class. The method of closing the prongs by applying manual pressure against the prongs is objectionable also 15 because of the danger of catching a finger or hand between the prongs being closed.

It is an object of this invention to provide a lever for closing the prongs of a loose leaf binder safely and with a minimum of effort. It is a further object of this invention to provide a prong closing lever that will not interfere with the normal use of the binder. It is a further object of this invention to provide a prong closing lever that will lie adjacent to the cover plate of the binder mechanism as long as the prongs of the binder are in closed position, and will automatically move to operative position whenever the prongs are opened, regardless of whether the prongs are moved to open position manually or 25 by means of the opening lever. It is a further object of this invention to provide a prong closing lever that is economical to manufacture and assemble, and is efficient and durable in use. Other objects of this invention will become apparent 30 upon reading the following description taken in conjunction with the accompanying drawing in which:

Figure 1 is a perspective view of a loose leaf binder embodying the invention;

45 Figure 2 is a fragmentary perspective view illustrating the prong closing lever when the prongs are in closed position;

50 Figure 3 is a fragmentary perspective view illustrating the lever supporting means and the spring for holding the lever against the cover plate; and

55 Figure 4 is a perspective view of the binder mechanism with parts removed showing the relationship of parts when the prongs are opened.

In the drawing, the reference numeral 2 des-

ignates a back member of a loose leaf binder. A pair of covers 3 are hingedly connected to the opposite edges of the back member. A ring metal 4 is secured to the back member 2 in any suitable manner.

The ring metal 4 includes a pair of toggle plates 5 arranged in side by side relationship within a back plate 6. The longitudinal edges of the back plate are bent to form flanges 7 adapted to embrace the outer edges of the toggle plates 10. The inner edges of the toggle plates 5 are maintained in abutting relationship by means of conventional buttons 8. A plurality of prongs 9 are secured to the toggle plates 5 in any suitable manner. The prongs on opposite plates are 15 preferably mated to form rings, as shown in Figures 1 and 4. It is obvious, however, that any suitable sheet retaining prongs may be substituted for the divided ring prongs. A cover plate 10 has its outer edges formed to embrace the 20 edges of the back plate. One end of the cover plate 10 is bent, as indicated at 11, Figure 1, to close the end of the ring metal and to give it a finished appearance.

One end of the ring metal is provided with 25 a conventional ring opening lever 12. The lever 12 is pivoted on the back plate 6, and has a foot portion 13 (Figure 4) adapted to lift the inner edges of the toggle plates to open the prongs when the finger piece of the lever 12 is 30 depressed. The lever 12 is not essential to my invention, but it is generally preferable to have some form of booster lever to open the prongs of the binder.

A supporting bracket 14 has a base portion 15 35 (Figure 3) secured to the underside of the back plate 6 in any suitable manner, such as welding, riveting or the like. The toggle plates 5 are notched to provide an aperture 16 through which the upright portion of the bracket extends. The 40 cover plate 10 is provided with an aperture 17 larger than the aperture 16. The upper end of the supporting bracket 14 is bifurcated to form two flanges 18.

A prong closing lever 19 is pivotally secured 45 to the supporting member 14 by means of a pin 20 which passes through the flanges 18. A coiled spring 21 surrounds the pin 20 and has one end bearing against the underside of the lever and the other end bearing against a horizontal portion of the bracket 14. The spring exerts a constant force tending to urge the lever 19 against the cover plate. This spring action also prevents the prong closing mechanism from rattling. The prong closing lever 19 has a finger piece 22 55

shaped to conform to the contour of the end 11 of the cover plate 10 so that the lever will be as inconspicuous as possible when in inoperative position.

5 The lever 19 is provided with cam portions 23 which project through the aperture 17 in the cover plate to engage the toggle plates 5 on opposite sides of the aperture 16. The cam portions 23 are so shaped that when the toggle plates 5 are 10 moved to open position, the prong closing lever is moved from its inoperative position shown in Figure 2 to the operative position shown in Figure 4 against the pressure of the coiled spring 21.

Since the movement of the toggle plates causes 15 the movement of the lever, it makes no difference whether the prongs are opened by means of the booster lever 12, or by manual force applied directly to the prongs. The prong closing lever 19 will always be in operative position whenever 20 the sheet retaining prongs are in open position. The position of the toggle plates when the prongs are in open position, as shown in Figure 4, will maintain the lever 19 in operative position until the toggle plates are moved into prong closing 25 position. The spring 21 will force the lever 19 against the cover plate when the prongs are closed regardless of how they are closed.

It will be seen that I have devised a simple and 30 efficient prong closing lever that is automatically moved to operative position whenever the prongs are moved to open position, and is maintained in operative position until the prongs are closed. The leverage of the prong closing mechanism is sufficiently great so that the prongs of a loose leaf 35 binder may be closed with little effort even in cases where the prongs are held under extremely heavy tension. The clearance between the finger piece of the prong closing lever and the ring closest thereto is always great enough to obviate 40 any danger of catching the finger of the user between the prongs.

While I have described a preferred embodiment 45 of my invention in detail, it will be understood that the description thereof is illustrative rather than restrictive, as many details may be modified or changed without departing from the spirit or scope of my invention. Accordingly, I do not desire to be restricted to the exact construction described, except as limited by the appended claims.

50 I claim:

1. In a loose leaf binder, a ring metal including a plurality of sheet retaining prongs, a lever operable to move said prongs to closed position, spring means urging said lever toward inoperative 55 position, and means to move said lever to operative position against the action of said spring means when said prongs are moved to open position.

2. In a loose leaf binder, a ring metal including 60 a plurality of sheet retaining prongs, a lever operable to move said prongs to closed position, spring means urging said lever toward inoperative position, and means to maintain said lever in operative position against the action of said spring means when said prongs are in open position.

3. In a loose leaf binder, a ring metal including 65 a pair of toggle plates and a plurality of sheet retaining prongs secured to said toggle plates, a lever positioned above said toggle plates having a cam portion operable to move said prongs to closed position, said lever remaining in inoperative position as long as said prongs remain in closed position, and automatic means to move 70

said lever to inoperative position when said prongs are manually moved to closed position.

4. In a loose leaf binder, a ring metal including 5 a pair of toggle plates and a plurality of sheet retaining prongs secured to said toggle plates, and a lever pivotally supported above said toggle plates, said lever engaging said toggle plates to move said prongs to closed position, said toggle plates being adapted to move said lever from inoperative to operative position when said prongs are moved 10 to open position.

5. In a loose leaf binder, a ring metal including 15 a pair of toggle plates and a plurality of sheet retaining prongs secured to said toggle plates, a lever engaging said toggle plates to move said 20 prongs to closed position, and spring means urging said lever toward inoperative position, said toggle plates maintaining said lever in operative position against the action of said spring means when said prongs are in open position.

6. In a loose leaf binder, a ring metal including 25 a pair of toggle plates and a plurality of sheet retaining prongs secured to said toggle plates, a lever operable to move said prongs to closed position, said toggle plates maintaining said lever in 30 operative position when said prongs are in open position, and spring means adapted to move said lever to inoperative position when said prongs are moved to closed position manually.

7. In a loose leaf binder, a ring metal includ- 35 ing a pair of toggle plates and a plurality of sheet retaining prongs secured to said toggle plates, and a lever pivotally supported above said toggle plates, said lever being operable to move said prongs to closed position, said toggle plates being 40 adapted to move said lever from inoperative to operative position when said prongs are moved to open position and to maintain said lever in operative position as long as said prongs remain in open position.

8. In a loose leaf binder, a ring metal including 45 a plurality of sheet retaining prongs and a cover plate, a supporting member secured to said ring metal, a lever pivotally secured to said supporting member, said lever being operable to move 50 said prongs to closed position, and spring means holding said lever against said cover plate when said prongs are in closed position.

9. In a loose leaf binder, a ring metal including 55 a plurality of sheet retaining prongs, a supporting member secured to said ring metal, a lever, a pin pivotally securing said lever to said supporting member, said lever being operable to move said prongs to closed position, and means to move 60 said lever from inoperative to operative position when said prongs are moved to open position.

10. In a loose leaf binder, a ring metal including 65 a plurality of sheet retaining prongs, a supporting member secured to said ring metal, a lever pivotally secured to said supporting member, said lever being operable to move said prongs to closed position, spring means urging said lever towards 70 inoperative position, and means to maintain said lever in operative position against the action of said spring means when said prongs are in open position.

11. In a loose leaf binder, a ring metal including 75 a back plate, a pair of toggle plates mounted in said back plate, a plurality of sheet retaining prongs secured to said toggle plates, and a cover plate embracing the longitudinal edges of said back plate, a supporting member secured to said back plate, a lever pivotally secured to said supporting member, said lever having a cam portion engaging said toggle plates to move said prongs 80

to closed position, and spring means holding said lever against said cover plate when said prongs are in closed position.

12. In a loose leaf binder, a ring metal including 5 a back plate, a pair of toggle plates mounted in said back plate, a plurality of sheet retaining prongs secured to said toggle plates, and a cover plate embracing the longitudinal edges of said back plate, a supporting member secured to said 10 back plate, and a lever pivotally secured to said supporting member above said cover plate, said lever having a cam portion engaging said toggle plates to move said prongs to closed position, and said toggle plates being adapted to move said lever 15 to operative position when said prongs are moved to open position.

13. In a loose leaf binder, a ring metal including a back plate, a pair of toggle plates mounted in said back plate, a plurality of sheet retaining 20 prongs secured to said toggle plates, and a cover plate embracing the longitudinal edges of said back plate, a supporting member secured to said back plate, a lever pivotally secured to said supporting member, said lever having a cam portion 25 engaging said toggle plates to move said prongs to closed position, and spring means urging said lever toward inoperative position, said toggle

plates being adapted to maintain said lever in operative position against the action of said spring means when said prongs are in open position.

14. In a loose leaf binder, a ring metal including 5 a back plate, a pair of toggle plates mounted in said back plate, a plurality of sheet retaining prongs secured to said toggle plates, and a cover plate embracing the longitudinal edges of said back plate, a supporting member secured to said 10 back plate, and a lever pivotally secured to said supporting member above said cover plate, said lever having a cam portion engaging said toggle plates to move said prongs to closed position.

15. In a loose leaf binder, a pair of toggle plates, 15 a cover plate provided with an aperture spaced from one end, a lever having cam portions intermediate its ends depending through said aperture to depress said toggle plates.

16. In a loose leaf binder, a ring metal including 20 a plurality of sheet retaining prongs, a back plate and a cover plate, a supporting member secured to said back plate and projecting through said cover plate, and a lever pivotally secured to said supporting member, said lever being operable to 25 move said prongs to closed position.

GEORGE H. DAWSON.
